UNITED STATES PATENT OFFICE.

WILLIAM C. CROSS, OF BOSTON, MASSACHUSETTS.

PAPER-BAG MACHINE.

SPECIFICATION forming part of Letters Patent No. 243,858, dated July 5, 1881.

Application filed May 17, 1881. (No model.)

To all whom it may concern:

Be it known that I, WILLIAM C. CROSS, of Boston, Massachusetts, have invented certain new and useful Improvements in Machinery for Making Paper Bags, of which the following is a specification.

My invention relates to machinery for making satchel-bottom paper bags, and has particular reference to that portion of the machinery by which the second and the third or final folds of the satchel-bottom are made.

The characteristic feature of my invention mainly resides in the employment, for the purpose of making these two folds, of a pair of rotating power-driven rolls, the one carrying two clamping-jaws and the other two blades, the two rolls running in contact, or substantially so, and the jaws and blades carried by them being so positioned with respect to one another and to the diamond-folded blank passing between the rolls that the jaws and their co-operating blades will successively meet on the blank along the proper lines of fold, and will coact to make the last two folds of the satchel-bottom as the blank passes along between the rolls. I in this way reduce to the minimum the number of working parts required to make the last two folds, simplifying and reducing the cost of the machine, and obtaining a mechanism accurate in operation and capable of doing rapid work.

The nature of my invention and the manner in which the same is or may be carried into effect will be understood by reference to the accompanying drawings, in which—

Figure 1 is a sectional side elevation of so much of machine as is needed for the purpose of explaining the invention. Fig. 2 is a like view of the same parts, with the folding-rolls in a position different from that which they occupy in Fig. 1. Fig. 3 is a like view of the folding-rolls in a position different from those in which they are shown in Figs. 1 and 2. Fig. 4 is an end elevation of the rolls, their supporting-frame, and the cams attached thereto for actuating the jaws and blades carried by the rolls. Fig. 5 is a modification hereinafter referred to. I have in Figs. 1, 2, and 3 omitted, for the sake of clearness, the gearing by which the rolls are driven and the frame in which they are supported, these devices being within

the knowledge of the mechanic and unnecessary to an understanding of my invention.

A A' are paste-rolls, to which the diamond-folded blank, with diamond fold uppermost and in front, is delivered in any suitable manner—as, for instance, from a diamond-fold-forming mechanism operating upon the plan set forth in my Letters Patent No. 221,531, of November 11, 1879. The paste-roll A is made, as customary, with central paste ribs or ridges, as shown in my Letters Patent No. 239,457, of March 29, 1881, supplied with paste from a suitable source, and acting to deliver paste in the usual way along the proper lines on the diamond of the blank. The blank is by the rolls A A' pasted and fed along over the table A² to the folding-rolls B C, which I shall now proceed to describe.

The roll B carries two clamping-jaws, a a', counterparts of one another in construction, but timed differently as to their movements. Jaw a acts on the front flap, x, of the blank w to make the second fold. It is mounted on a rock-shaft, b, in a recess, c, in the roll B, and is intended to move to and from the side d of said recess, which is in effect a stationary clamping-surface, against which the jaw presses that portion of the blank tucked down between them by the blade, hereinafter described. The rock-shaft b projects from one end of the roll B, and on its projecting end is mounted a crank-arm or stud, e, which is acted on by a stationary cam, f, fixed to the frame K of the machine, as indicated in Fig. 4, and preferably is adjustable thereon. The cam holds the jaw open, and is so formed that at the proper time it will permit the arm e to clear it, thus releasing the jaw, which, by the stress of a spiral spring, g, encircling its rock-shaft, as indicated by dotted lines in Fig. 4, and attached at one end to said shaft or jaw and at the other to the roll, is caused to at once close against the stationary clamping-surface d.

In the roll C is mounted a blade, h, which co-operates with the jaw a. This blade is mounted in a radial recess in the roll C, and preferably is capable of sliding back and forth therein, being pushed outward by a spring or springs, i, and moved inward against the stress of said spring or springs by cams j, fixed to the frame of the machine, (preferably in an ad-

justable manner,) as indicated in Fig. 4, which act on friction studs or rollers *k*, one at each end of the blade.

The rolls *B C*, one or both, are mounted in 5 spring-boxes, so that they shall bear against one another with yielding pressure in order to adapt themselves to the varying thickness of the blank passing between them. They revolve at the same peripheral speed, and are so 10 placed and timed that during their rotary movement the clamp-jaw *a* and blade *h* will meet at the time when the blank has entered far enough between the roll to bring the front flap, *x*, between them on the proper line of fold. 15 The cams *fj* are so placed that at the time the clamping-jaw *a* and blade *h* come opposite one another the blade protrudes from its roll, and the jaw is open, so that the blank will tuck a portion of the front flap, *x*, along the proper 20 line of fold down in the bite of the jaw, as indicated in Fig. 1, just at the time the latter is about to clear its cam. Further rotary movement of the rolls causes the blade to be lifted by the cams *j* simultaneously with the release 25 of the jaw from the influence of its cam *f*, and the jaw will thus close tightly on the blank and carry it around until caused to release hold thereon by the cam, as indicated in Fig. 2. In the interim the jaw, as seen in the 30 figure, has carried the bag around far enough under a wiper cross-bar or idle-roll, *D*, to wipe back and down the front point or flap, *x*, along the line of fold, thus completing the second fold, and it releases its hold upon the folded 35 front end of the bag in time to permit that end to rise or stand away from the periphery of the roll *B* far enough to pass above a second wiper cross-bar or idle-roll, *E*, which is used as a convenient adjunct to complete the 40 third or final fold.

In rear (relatively to direction of feed) of the jaw *a* is a second jaw, *a'*, hereinbefore referred to. This jaw and its adjuncts *b' c' d' e' f'* are counterparts of jaw *a* and its adjuncts 45 *b c d e f*, and there is combined with said jaw also a spring similar to spring *g*. The cam *f'* is, however, placed on the side of the machine opposite to that on which cam *f* is placed, and arm *e'* projects from the end of the roll opposite 50 site to that from which arm *e* projects. Cam *f'* is also shorter than cam *f*, so that the jaw *a'* may retain its hold on the blank for a longer time than does the jaw *a*.

In the roll *C*, and intended to coact with 55 jaw *a'*, is a blade, *h'*, with adjuncts *i' k'*, similar to blade, *h* and adjuncts *i k*, already described. The studs *k'* are acted on by the same cams, *j*, which influence the studs *k*. These devices *a' h'* are placed at such a distance in rear of those 60 devices *a h* already described that they will meet at a time when the blank *w* has passed far enough along between the rolls *B C* to bring said parts *a' h'* opposite the proper line of fold on the rear flap, *y*, of the diamond fold. 65 The blade *h'* tucks the rear flap of the diamond along this line down into the bite of the jaw

a', as seen in Fig. 2, tucking along with it, also, the underlying body of the blank, and then is raised by cams *j* just as the jaw, released from the influence of the cam *f'*, closes upon the 70 part tucked between it and the face *d'*. By the continued movement of the rolls the blank is carried around that portion of the blank in front of the point where the jaw *a'* has its hold, being deflected or shunted off away from the 75 roll *B* in the space between the wipers *D E* until jaw *a'*, still holding the blank, travels under and past the lower wiper bar or roll, *E*, as indicated in Fig. 3, which has the effect of 80 folding back and down upon the body of the bag, in rear of the point where it is held by the jaw, that part of the blank in front of that point, as shown in the figure referred to, thus in effect doubling the bag upon itself and making a blind fold therein, but at the same time 85 folding down the third or final fold, pressing all the folds, and virtually completing the satchel-bottom. The jaw *a'* retains its hold on the blank until nearly reaching the position shown in Fig. 1, at which time its cam *f''* opens 90 it, thus releasing the blank, which drops from the folding mechanism upon the upper end of a carrier, *F*, and is by that instrumentality conveyed to the drier. The carrier arrangement shown serves to straighten out also the 95 blind fold in the bag. That fold of the bag which is doubled back upon the body naturally opens, thus catching over the upper end of the carrier shown in Fig. 1, and the fold, as the bag is carried along, naturally straightens 100 out, as seen in Fig. 2.

It will thus be seen that by the employment of two rolls only—the one having the pair of spring and cam controlled clamping-jaws and the other a pair of coacting blades—I am enabled at each revolution of said rolls to make on a diamond-folded blank passing between them the last two folds of the satchel-bottom. 105

This improvement renders it feasible for me to employ but three rolls for the purpose of 110 making both the diamond fold and the last two folds of a satchel-bottom. A mechanism adapted to obtain this result is shown in Fig. 5 in sectional side elevation. Like lettered parts in this figure represent correspondingly lettered 115 parts in the figures hereinbefore described. The clamping-jaw and blade-carrying rolls *B C* are, in so far as concerns the making of the second and final folds of the satchel-bottom, the same as those already described; but the 120 roll *B* possesses in this case the additional characteristic of being one of a pair of diamond-fold-forming rolls, of which the other is shown at *G*. This roll *G* is provided with a vibratory nipper, *l'*, and the roll *B* is provided 125 in advance of the second-fold clamping-jaw *a* with a like nipper, *l*, the two being controlled by springs and cams *m m'*, and constituting in effect a pair of diamond-fold-forming cylinders or rolls, constructed, arranged, and operating 130 to make the diamond fold, as shown and described in my Letters Patent No. 239,457, of

March 29, 1881. It will be understood, of course, that I use, in conjunction with said rolls, elastic or yielding opening fingers or their equivalent, as specified in said Letters Patent, 5 for the purpose of opening the mouth of the blank to permit the nippers to enter therein and take hold of the plies. The rolls rotate in the direction indicated by the arrows and move at the same surface-speed. The nippers $l l'$ are shown as about taking hold of plies 11 of the blank. Continued movement of the rolls causes the nippers to close on these plies, the blank thus held being drawn along between the rolls, and its mouth end being gradually spread apart by the two moving diverging surfaces on which its plies are held. The cams $m m'$ are so adjusted that the nipper l' on roll G releases its hold before the nipper l on the roll B does. The latter retains its hold 20 on the blank, carrying the point which it holds of the diamond fold thus partially formed along between roll B and the presser and paste roll A, which presses out the diamond fold and deposits the two lines of paste thereon, as 25 usual. After carrying the blank along still farther until the point of the diamond has entered between the rolls B C the nipper releases the blank. The clamping-jaw a is at such a distance in rear of nipper l that it will be under that part of the front flap of the diamond 30 opposite the line of fold for the second fold, and the two rolls B C, after the blank has entered between them, act on it with their jaws and blades $a a' h h'$ in the manner hereinbefore described, the completed bag, after its 35 folded part passes the last wiper, E, being directed off and discharged from the machine by any appropriate means.

It will thus be seen that a roll provided with 40 a nipper or equivalent ply-grasping device and a pair of clamping-jaws coacts, on the one hand, with a roll having a similar ply-grasping device to make the diamond fold, and on the other hand with a roll carrying a pair of blades 45 to make the second and the third or final folds, and that consequently I am enabled with three rolls to make a satchel-bottom.

In the drawings I have shown, in connection 50 with the clamping-jaws, light spring-lifters n , which are seated in recesses in the roll B, being fastened at one end therein and extending crosswise of the jaws, in which are notches, which will permit these strips to be depressed by the blades below the acting faces of the 55 jaws. It is the function of these strips to lift and disengage from the recesses c in the rolls the blank as soon as it is released from the jaws. These devices, however, are not here claimed, inasmuch as they form part of an 60 other application by me for Letters Patent. I also, as shown in Fig. 4, make notches at $o o$ in the blades, the object of this being to pre-

vent the blades from coming in contact with the lines of paste on the face of the diamond fold.

Having described my improvement, what I claim, and desire to secure by Letters Patent, is—

1. In machinery for making the second and final folds of a satchel-bottom on a diamond-folded blank, the combination of a rotating jaw-roll and two spring and cam controlled clamping-jaws carried by the same with a blade-carrying roll provided with two blades, adapted to coact the one with one clamping-jaw on the leading flap of the diamond, the other with the other clamping-jaw on the rear flap of the diamond, these parts being combined and arranged for joint operation substantially as hereinbefore set forth. 65

2. The combination of the clamping-jaw roll, the two vibratory clamping-jaws carried by the same and actuated to move substantially as described, the blade-roll, the two blades carried by the same, and the wiper cross bars or 85 rolls, the combination being and acting substantially as hereinbefore set forth.

3. The combination, substantially as hereinbefore set forth, of the clamping-jaw roll and the two spring and cam controlled jaws carried by the same, the blade-roll and two blades carried by the same, the wiper cross bars or 90 rolls, and the carrier.

4. The clamping-jaw roll provided with a 95 ply-grasping nipper and two clamping-jaws, arranged and operated to move substantially at the times and in the manner described, in combination with a nipper-roll and vibratory nipper carried by the same, co-operating with said clamping-jaw roll to make the first or the 100 diamond fold, and a blade-roll carrying two blades, arranged to co-operate with the jaws on said clamping-jaw roll to make the second and the final folds, substantially as hereinbefore set forth. 105

5. The combination, with the clamping-jaw and nipper-roll carrying clamping-jaws and a nipper arranged and operated to move at the times and in the manner substantially as described, of the nipper-roll and blade-roll and 110 their adjuncts and the paste-roll, substantially as hereinbefore shown and set forth.

6. The combination, substantially as hereinbefore set forth, of nipper-roll G, clamping-jaw and nipper-carrying roll B, and paste-roll A, 115 blade-carrying roll C, and wiper bars or rolls D E.

In testimony whereof I have hereunto set my hand this 10th day of May, A. D. 1881.

WILLIAM C. CROSS.
